CLAIM

The ornamental design for an electrophoresis sequencing apparatus tray, as shown.

DESCRIPTION

FIG. 1 is a perspective view of an electrophoresis sequencing apparatus tray, showing our new design;
FIG. 2 is a right side elevational view thereof;

FIG. 3 is a left side elevational view thereof;
FIG. 4 is a top plan view thereof;
FIG. 5 is a front elevational view thereof;
FIG. 6 is a bottom plan view thereof; and
FIG. 7 is a rear elevational view thereof.
